UNITED STATES PATENT OFFICE.

JOHN M. DEXTER, OF ELMIRA, NEW YORK.

LAMP.

SPECIFICATION forming part of Letters Patent No. 236,937, dated January 25, 1881.

Application filed October 8, 1879.

To all whom it may concern:

Be it known that I, JOHN M. DEXTER, of Elmira, in the county of Chemung and State of New York, have invented certain new and useful Improvements in Lamps; and I do hereby declare the following to be a full, clear, and exact description of the invention, such as will enable others skilled in the art to which it appertains to make and use the same, reference being had to the accompanying drawings, and to letters of reference marked thereon, which form part of this specification.

My invention is a lamp constructed, as fully described hereinafter, so as to avoid the danger of breakage incident to ordinary constructions, prevent oil from passing to the outside of the reservoir, the danger of the burner becoming loose, and to facilitate the manufacture.

20 In the drawings, Figure 1 is a sectional elevation of sufficient of a lamp to show my improvements. Fig. 2 is a perspective view, and Fig. 3 a sectional view, showing the ordinary mode of securing the burner.

25 In the construction of ordinary lamps having reservoirs of vitreous materials, it has been common to provide the reservoir A with an upwardly-projecting neck, b, to which is cemented a metal cap or collar, H, having an 30 internal-threaded socket adapted to receive the threaded projection c of the burner I. Owing to the projection of the neck above the reservoir it can be readily struck, and is frequently broken in this manner, this being one 35 of the common causes of the breaking of such lamps. I remedy this by forming the reservoir with an internal neck—that is, with a neck, b, projecting downward into the reservoir, instead of extending above it—so that instead of being the most exposed it is the best 40 protected part of the lamp.

Another objection to lamps having vitreous reservoirs is the liability of the oil to pass downward over the outside of the reservoir, 45 flowing either from the joint between the latter and the cap or collar H, dripping from the wick above the wick-tube, or from the spout of the filling-vessel. Attempts have been made to obviate this by forming the caps or 50 collars with basins and grooves to receive the oil dripping from the burner, and carrying it back into the reservoir; but it will be apparent that in such case there is a joint between the cap and the burner, outside of the drip- 55 opening, through which the oil may exude.

Thus, if the drip-opening was at x, Fig. 3, the outside joint at y would permit the oil splashed up in moving the lamp to escape when there was any internal pressure or any capillary action. To avoid such objections it has been 60 proposed to make the body of a lamp with a lateral flange at the top, forming an oil-receptacle; but it is not possible to form such flange in the same piece with the vitreous body, and if made of other material the outside joint would be attended with the same 65 objections as when a cap is used. Moreover, the outside flanges, even if this could be made, would be so exposed as to be quickly broken. I obviate these objections by forming threads 70 c in the neck b, and by making channels E across such threads, and by depressing the top of the reservoir to form a basin, B, the inclined bottom of which directs all oil spilled or flowing in any way onto the top of the reservoir 75 to the channels E, through which it flows into the reservoir.

It will be seen that by forming the threads C in the neck there can be no joint outside of such threads, as heretofore, communicating 80 with the reservoir, and affording a means of exit, that the possibility of the burner dropping off from loosening of the attachment, as when using a cemented cap, H, is absolutely 85 prevented, and that the basin B can be readily formed during the ordinary manufacture of the lamp, and without presenting any portion of the lamp in an exposed situation.

I am aware that it is not new to form an oil-channel across the threads and communicating 90 with drip-cup; but I know of no instance where such channels are formed in the outside joint, connecting the metallic and vitreous portions of the lamp.

I claim—

The lamp-reservoir shown and described, consisting of the bowl A, having the basin B extending downward into the body of the bowl, and provided with a threaded neck extending downward from the basin, said neck having 100 channels E crossing the threads, substantially as set forth.

In testimony that I claim the foregoing I have hereunto set my hand and seal this 3d day of October, 1879.

JNO. M. DEXTER. [L. S.]
